UNITED STATES PATENT OFFICE.

CHARLES E. A. SPIEGEL, OF NEW YORK, N. Y.

DESIGN FOR A PNEUMATIC-TIRE TREAD.

Application filed October 10, 1923. Serial No. 7,465. Term of patent 3½ years.

To all whom it may concern:

Be it known that I, CHARLES E. A. SPIEGEL, a citizen of the United States, residing at New York city, borough of Manhattan, county of New York, and State of New York, have invented a new, original, and ornamental Design for Pneumatic-Tire Tread, of which the following is a specification, reference being had to the accompanying drawing, forming part thereof.

Fig. 1 is a detail elevation of the pneumatic tire tread; and

Fig. 2 is a cross sectional view of the tire and tread.

I claim:—

The ornamental design for a pneumatic tire tread as shown.

CHARLES E. A. SPIEGEL.
